UNITED STATES PATENT OFFICE.

JOHN A. WILSON, OF FORT WAYNE, INDIANA.

PAPER-CLIP.

1,086,258.

Specification of Letters Patent.

Patented Feb. 3, 1914.

Application filed January 8, 1913. Serial No. 740,846.

To all whom it may concern:

Be it known that I, JOHN A. WILSON, a subject of the King of Great Britain, residing at Fort Wayne, in the county of Allen 5 and State of Indiana, have invented new and useful Improvements in Paper-Clips, of which the following is a specification.

This invention relates to paper clips; and it has for its object the provision of an article of this character which may be constructed of a single piece of springy material having remote contacting surfaces and a main connecting element between the surfaces and normally occupying the same general plane therewith and adapted to overlie one side of the paper or article with which it is connected and to exert its pressure immediately along the axial center of each of the gripping surfaces, whereby to maximize 15 the locking efficiency of the clip and positively prevent its accidental derangement from the papers.

A further object of the invention is to provide a clip which will be so constructed as to facilitate its connection with or its disconnection from the papers.

With these and other objects in view, the invention consists of certain novel features of construction, combination and arrangement of parts, as will be hereinafter described and claimed.

In the accompanying drawings Figure 1 is a perspective view of the clip; Fig. 2 is a plan view thereof, showing the application 35 of the same to one of the corners of a package of papers; Fig. 3 is a similar view, looking at the reverse side thereof; Fig. 4 is another view similar to Fig. 2, showing the application of the clip to one of the longitudinal sides of the package; and Fig. 5 is an edge view of the clip.

The clip is constructed from a single length of springy wire bent terminally to provide companion gripping surfaces 1, 45 which consist of a plurality of convolutions 2 occupying the same general plane and arranged so that the large outermost convolutions are offset, as at 3, into a connecting or pressure bar 4, the offset portions 2 of 50 said outermost convolutions serving to hold the connecting portion 4 alined with the innermost small convolutions of the surfaces 1,

as clearly illustrated in Fig. 1 of the drawing. The bar 1 is straight throughout whereby to present a relatively broad contacting surface against one side of the package of sheets with which the clip is associated and to apply its pressure against the sheets at one side of the surfaces 1, whereby to positively cause the papers or sheets to be 60 securely interposed between the surfaces 1 and bar 4, respectively. The convolutions 5 of the surfaces 1 are spaced from the connecting offset portions 3 of the outermost large convolutions 1, whereby to form intervening paper guiding passages 6 therebetween to facilitate the initial application of the clip to papers as will be seen.

The clip is so constructed that it may be applied either to the corners of the package or to the sides thereof, as shown in the different figures of the drawings. The bar 4 may be disposed outermost upon the package so that the clip will not conceal the written matter contained on the sheet, while the 70 relative arrangement of the bar 4 and the surfaces 1 is such as will maximize the gripping efficiency of the article. The intervening spaces 6 which are formed incident to such construction has been found to 75 greatly facilitate the work involved in placing the clip on the sheets.

From the foregoing description, taken in connection with the accompanying drawings, the construction and operation of the 85 invention will be readily understood without requiring a more extended explanation.

Various changes in the form, proportion and the minor details of construction may be resorted to without departing from the 90 principle or sacrificing any of the advantages of this invention, as claimed.

Having thus described my invention, what I claim is:—

1. A paper clip constructed from a single 95 length of springy wire having terminal contacting surfaces consisting of many convolutions and a connecting portion extending into the outermost convolutions of said surfaces and offset whereby to be alined with 100 the innermost convolutions of said surfaces and occupying the same general plane therewith.

2. A paper clip constructed from a single

length of springy wire having groups of identically formed convolutions, the convolutions of each group occupying the same general plane with each other, a connecting bar between the respective groups and offset portions connecting the outermost convolutions of each group with said bar and spaced from the adjacent convolutions

whereby to form intervening paper guiding passages therebetween. 10

In testimony whereof I affix my signature in presence of two witnesses.

JOHN A. WILSON.
